CLAIM

The ornamental design for a suspended diffused lighting fixture for commercial films and photography, as shown and described.

DESCRIPTION

FIG. 1 is a top, rear, right side perspective view of a suspended diffused lighting fixture for commercial films and photography, showing my new design;

FIG. 2 is a rear elevational view thereof;

FIG. 3 is a top plan view thereof;

FIG. 4 is a bottom plan view thereof;

FIG. 5 is a right side elevational view, the left side elevational view being the mirror image thereof; and,

FIG. 6 is a front elevational view.

The cross-hatching which indicates a light diffusing fabric is partially shown for ease of illustration, it being understood that the cross-hatching is continuous over the surfaces on which it partially appears.
